UNITED STATES PATENT OFFICE

FRANK PEREBENDA, OF HARRISON, NEW JERSEY

CLOTHESLINE SUPPORT

Application filed February 14, 1929. Serial No. 339,776.

The invention relates to endless clothes lines and supports for the looped ends thereof whereby the line with clothes pins or hangers supporting the clothes to be dried may be passed around the pulleys of the supports at either looped end of the clothes line or both of them and whereby the opposite laps or stretches of the line may be used for hanging instead of only using one lap, thereby increasing or doubling the capacity of the clothes line.

Another object of the invention is to provide a pulley support for each looped end of the endless clothes line having a casing containing the mechanism which is thereby protected from inclement weather and which includes means for supporting the stretches of the line entering the casing and guiding means for directing the line around the pulley and retaining the same from displacement, the casing having a cover for obtaining access to the interior mechanism and also provided with supporting bracket capable of angular adjustment vertically as desired according to the position to support the device and the nature of the support.

Another object of the invention is to provide gripping devices for the opposite ends of the line adjacent the pulley at the looped end of the line which as the pulley rotates alternately grips and releases the line as moved along in hanging or removing the clothes, the gripping action being such that, should only a portion of the line have clothes hung thereon or should certain articles be heavier than others at certain portions of the line which together with the sagging of the line would ordinarily cause the line to move until an equilibrium is established, will hold the line against movement so that the point on the line at which the clothes are being hung or removed are not shifted away from the point at which this operation is being effected.

Another object of the invention is to provide means for joining the ends of the clothes line in alinement and which means serves as a take-up for shortening the line or as means for lengthening the same.

Another object of the invention is to provide novel clothes pins or spring clips for

hanging clothes on the line, which are so constructed as to permit the same to be placed at convenient points along the line and adapted to travel with the line without obstructing the supporting device or its pulley.

With the above general objects in view and others that will appear as the nature of the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views,

Fig. 1 is a plan view partly in section of one of the clothes line supports;

Fig. 2 is a sectional elevation taken on section line 2—2 of Fig. 1;

Fig. 3 is an enlarged fragmentary detail showing a guide pulley and one of the gripping means for checking and releasing the line;

Fig. 4 is an enlarged vertical sectional view of the device shown in Fig. 1 and showing the supporting brackets;

Fig. 5 is a perspective view of one of the clothes pins or gripping and releasing means; and

Fig. 6 is a perspective view of a connector for the ends of the line.

Referring to the drawings in detail 7 designates a rectangular housing or casing 8 preferably of metal having hinged covers 9 pivoted at the ends as indicated at 10 to swing upwardly and recessed at the inner edges as indicated at 11 to accommodate a goose-necked supporting arm 12 having inner and outer ends, the outer ends being pivoted as at 13 between the arms 14 of a slotted or bifurcated bracket 15 having suitable openings for attaching it to a support. The outer end of the arm 12 is provided with a flat plate 16 having a plurality, preferably a pair of openings 17 adapted to be engaged by a pin or bolt 18 disposed through the arms 14 so as to angularly adjust the arm 12 vertically according to the position in which it is 100

desired to support the casing 7 and its contained mechanism which will be subsequently described and also according to the nature of the support to which the bracket 14 is attached.

5 The front of the casing 7 is provided with a pair of spaced openings 18 which merge into a larger single opening 19 in the bottom of the casing, cut semi-circularly at the back.

10 Arranged across the casing is a supporting frame 20 which has a central sleeve 21 forming a socket receiving the depending outer end of the arm 11 and to which it is pinned or otherwise suitably fixed as indicated at 22.

15 The sleeve 21 rotatably receives the upper end of a vertical pulley shaft 23 having a pulley 24 at its lower end near the bottom of the casing, the grooved periphery of the pulley being preferably provided with a series of

20 upper and lower teeth 25 to guide and retain the clothes line 26 therein. The frame 20 is formed at the front with a substantially U-shaped portion 27 comprising a horizontal upper portion bent down to provide a vertical front portion and a horizontal inwardly extending bottom portion in the form of an arm which serves as a support for a bearing including a ball-cup 28 held in position by a screw 29. The bottom of the pulley 24

25 is recessed as at 30 to form a cooperating ball-cup fitted over the cup 28 with interposed ball-bearings 31 in the races thereof so that the pulley and the shaft will be properly supported for rotation with the minimum of friction.

30 Arranged around the pulley 24 and in horizontal alignment therewith but spaced therefrom is a U-shaped guide 32 the forward ends of which are positioned adjacent the front of the casing and the openings 18, and are bifurcated to provide upper and lower bearings 33 between which grooved star wheels 34 are journaled on vertical hangers or pins 35 suspended from extensions 36 on opposite

35 sides of the vertical front portion of the portion 27 of the frame adjacent the top thereof. The pairs of spaced arms of the star wheels 34 operate in the path between the bearings 33 and support and guide the opposite sides 40 of the line around the pulley 24 and retain the line from displacement.

45 Fixed to the shaft 23 is a large pinion 37 which operates between the frame 20 and a strip 38 attached thereto in spaced parallel relation therebeneath at a transverse portion and this pinion meshes with a pair of smaller pinions 39 on opposite sides fixed to vertical shafts 40 and journaled in the frame. The transverse frame member 20 is mounted on 55 the sides of the casing through depending portions 41 as indicated at 42 and the lower ends of which extend inwardly as indicated at 43 for attachment to the dies of the guide 32 whereby the latter is supported in conjunction with the hangers 35. The portions

43 of the frame 20 carry slotted guides 44 in which plungers 45 are slidable and having engaging ends, the inner ends of the plungers projecting through slots 46 in the sides of the guide 32 and shaped to provide gripping members for engagement with the opposite sides of the line 26 on the pulley 24. These plungers are held in position by springs 47 and at their inner ends are formed with shanks 48 extending through slots 49 in the top portions of the guides 44, the lower portions of which are formed by the portions 43, and the upper ends of the shanks carry blocks 50 adapted to be alternately engaged by corners or high-points and the flat sides of rectangular cams or blocks 51 fixed to the shafts

55 40. In this way, as the line is moved along, the pulley 24 will be turned and with it the shaft 23 and pinion 37 to rotate the pinions 39 and the shafts 40. The blocks or cams 51 are similarly positioned so that their corners and frame faces, respectively, will simultaneously engage the blocks or impact members 50 and cause the alternate release of the gripping members 46 from the line by forcing

60 the same inwardly against the action of the spring 47 and the release of the same to permit the gripping of the line when the flat faces of the cams 51 are against the blocks 50. This will alternately grip and release the line

65 so that while it may be moved along against the action of these gripping members by pulling on the line, they will normally check or hold the line against movement and in service

70 act as brakes. In a long stretch of clothes line, if only part of the line be occupied by the clothes or if portions should be weighted more than another portion the line would

75 tend to shift, especially where the line sags and these checking devices insure that the line will stay where put so that the point on the line where the clothes are being hung or removed will always be in convenient position.

80 85 90 95 100 105 110 115 120 125 130

115 120 125 130

In order to join the ends of the line a connector or coupling device shown on Fig. 6 is employed. This device includes a pair of sections 52 of U-shaped closed section with their concaved faces towards each other, one section having spaced pivot ears 53 hinged or pivoted to the other section as indicated at 54. Each section has a pair of spaced openings 55 through the uppermost of which the ends of the line are extended and sealed in the concavities and finally extended through the lower openings where they may be knotted as indicated at 56 to anchor the ends.

The openings, especially the upper openings 55 are in alignment so as to bring the ends of the line in corresponding relation and a ring or band 57 is placed over the upper free ends of the sections 52 to hold them together. This connector may readily pass by the star wheels 30 and around the pulley 24

130

accommodated between the teeth 35 thereof as the line is moved along.

The clothes pins to be used are shown more particularly in Figs. 4 and 5 at 58 and have kerfs 59 of resilient material such as metal to frictionally grip the line and adapted to be moved along the same to any desired position. The upper portions of the pins may be provided with loops 60 to receive the lines or as a convenient means of stringing the clothes pins or spring clips. The pins are formed of strips of metal having arms 61 at the lower ends forming jaws adapted to cooperate with jaws 62, these jaws being preferably elongated. The jaws 62 are formed at the lower ends of strips 63 which are apertured at their lower ends and hung from headed pins 64 projecting from the shanks of the pins and are held out by spring 65 positioned between the shanks and the strips 63. The shanks of the pins are also formed at their opposite edges with extensions bent at right angles in the same direction to form parallel ears 66 between which the shanks or strips 63 of the jaws 62 are adapted to move guided by opposite pairs of extensions or lugs 67 at opposite edges of the strips 63. The ears 66 are provided with openings or slots 68 in which angular camming members 69 are pivoted as at 70, these camming members being substantially U-shaped to form handle portions 71 by which they may be turned to cause the portions 67 to engage the strips or shanks 63 of the movable jaws when the camming members are turned upwardly from the position shown on Fig. 5 to the gripping position shown on Fig. 4, when the handle 71 will be forced against the shanks of the pins 58 limited against further movement. This action against the springs 65 will force the jaws 62 in clamping relation with the jaws 61 to clamp and hold the clothes to be hung. This is conveniently done since the clothes pins are hung from the line.

It is thus seen that with this device the clothes can be conveniently hung or removed from the line and with the oppositely looped ends of the endless clothes line operating around the pulley on which the line travels, the line may be continually passed around the pulleys with or without the clothes hung therefrom, thereby permitting the entire length of the line to be used for hanging purposes and not only facilitating and hanging and removing the clothes but increasing the capacity of the line. The gripping or checking device serves as a convenient adjunct so as to check the movement of the line or to permit it to be easily moved along as desired.

While there is described herein a preferred embodiment of the present invention, it is nevertheless to be understood that minor changes may be made therein without de-

parting from the spirit and scope of the invention as claimed.

What I claim as new is:

1. A clothes line support comprising a frame having a shaft therein, a pulley carried by the shaft for rotation and adapted to have a line trained therearound, a gear on the shaft, said support permitting continuous travel of the line on the pulley, and means operated by the gear on the shaft for alternately gripping and releasing the line during its movement around the pulley to check movement of the line at times. 70

2. A clothes line support comprising a frame, a pulley carried by the frame for rotation and adapted to have a line trained therearound, said support permitting continuous travel of the line on the pulley, a gear train operated by the pulley, and means actuated by the gear train for alternately gripping and releasing the line during its movement around the pulley to hold the line against movement during the hanging and removal of the clothes, said means being actuated during the movement of the line and bringing the gripping means into action when the line is stationary. 80 85

3. A clothes line support comprising a frame, a pulley carried by the frame for rotation and adapted to have a line trained therearound, said support permitting continuous travel of the line on the pulley, and means for alternately gripping and releasing the line during its movement around the pulley to hold the line against movement during the hanging and removal of the clothes, said means being actuated during the movement of the line and bringing the gripping means into action when the line is stationary, said gripping and releasing means being geared to the pulley to be actuated during the rotation thereof. 95 100 105

4. A clothes line support comprising a frame, a pulley carried by the frame for rotation and adapted to have a line trained therearound, said support permitting continuous travel of the line on the pulley, and means geared to the pulley for alternately gripping and releasing the line during its movement around the pulley to hold the line against movement during the hanging and removal of the clothes, said means being actuated during the movement of the line and bring the gripping means into action when the line is stationary, said last named means being normally in gripping position. 110 115 120

5. A clothes line support comprising a supporting frame, a casing about the frame, a pulley in the casing to receive a line, a bracket for supporting the casing for vertical angular adjustment, said casing having front slots and a bottom opening, said pulley rotatably supported in a horizontal position in the casing, a guiding member around the pulley, and gripping and releasing means for 125 130

the line geared to the pulley to be actuated by rotation of the pulley during movement of the line and holding the line against movement when stationary.

6. A clothes line support comprising a frame, a casing about the frame, a pulley supported by the frame, said pulley having means for supporting and guiding a line thereon, a bracket for supporting the frame, 10 said casing having front slots and a bottom opening, said pulley being rotatably supported in a horizontal position in the casing, a guiding member around the pulley, and gripping and releasing means for the line operatively associated with the pulley to be actuated by rotation of the pulley during movement of the line and holding the line against movement when stationary.

7. A clothes line support comprising means for attaching the same to a base, a frame having upper and lower portions, a shaft rotatably carried in bearings in the upper and lower portions, a pulley on the shaft for receiving the clothes line to be supported, a 25 gear on the shaft, means carried by the frame for gripping the clothes line and releasing the same with a step by step movement, said means being geared to the first mentioned gear, and spring pressed means controlling the operation of the gripping and releasing means.

8. A clothes line support comprising means for attaching the same to a base, a frame having upper and lower relatively parallel 35 spaced portions, a housing about the frame, a shaft carried rotatably in bearing in the upper and lower portions, a pulley on the shaft for receiving the clothes line to be supported, a gear on the shaft, means carried by 40 the frame for alternately gripping and releasing the clothes line as it passes around the pulley with a step by step movement, positive means connecting said gripping means with the gear to actuate the same as the pulley is rotated, and spring actuated means for controlling the operation of the gripping and releasing means.

In testimony whereof I affix my signature.
FRANK PEREBENDA.
